RELAY CONTROL CIRCUIT

John E. Balint, Eugene, Oreg., assignor to Controls & Communications Company, Eugene, Oreg., a corporation of Oregon

Filed May 8, 1958, Ser. No. 733,993

4 Claims. (Cl. 317—137)

This invention relates to relay control systems and, more particularly, to a circuit for selective operation of one or more of a plurality of relays and automatic cancellation of all previously selected relays.

In various industrial applications where apparatus is controlled by actuation of relays, it is essential that one selected relay be placed in operation and, at the same time, other previously selected relays be returned to either inoperative or de-energized position.

It is the primary object of this invention to provide a simple circuit which will permit the sequential operation of relays in the aforesaid manner.

It is a particular feature of the invention that standard, commercially widely used relays may be utilized in a circuit application which heretofore required the use of special relays with additional contact elements.

In its broader aspect, the invention provides a circuit which enables the momentary actuation of an electromagnetic device, such as a relay, regardless of the duration of the actuating impulse and permits the cancellation of any or all electromagnetic devices previously held through normal holding contacts and, at the same time, actuates one or more other electromagnetic devices or relays in a similar holding manner.

Other objects and features will be apparent from the following description of the invention, pointed out in particularity in the appended claims and taken in connection with the drawing in which the figure shows a schematic circuit of the relay control system.

Referring to the drawing, the relays A and N represent a bank of relays of any number required for a particular system. Each relay in this bank is associated with an operating switch S_a through S_n . The energizing circuit for the relay A need only be described in detail inasmuch as the circuits of all other relays in the bank are identical and will be denoted by the same reference characters bearing primary indices.

Power is furnished from lines 1 and 2 which represent any suitable voltage source for energizing the windings of the various relays. For practical purposes this line is usually the available A.C. power. Terminal 3 of the winding of the relay A connects directly to the line 2. The latter may be regarded as the common or ground return of the system. The terminal 5 of the winding connects by means of the conductor 6 to the terminal 7 of the switch S_a .

The relay A has two pairs of normally open contacts 8 and 9 of which the former is the holding contact and the latter the working or utilization circuit contact. Since the invention is not concerned with the particular apparatus or instrumentality controlled by the relays but rather with the control of the relays, the contacts 9 and 9' show no electrical connection. It will be obvious that these may be used to close or open any desired circuit, depending upon the arrangement of the contacts and as many circuits as there are contact pairs.

The contacts 8 are the holding contacts and therefore

2

are connected on the one side to terminal 5 and on the other side to the line 1 in series with the normally closed contacts 4 of the relay R. The holding contacts of each of the relays A through N in the bank are similarly connected to their respective terminal 5' of the winding and to the contacts 4 of the relay R. Consequently, as will be seen in connection with the description of the operation of the system, the contacts 4, when opened, disconnect all holding contacts 8, 8', etc. from the line 1, thereby releasing all relays held in the bank.

The switches S_a through S_n are of the double-pole, single-throw type, preferably in the form of push buttons or other self-release construction. Each of these switches controls two distinct circuits from the lines 1 and 2. The first circuit of the switch S_a between contacts 11 and 12 applies current directly to the winding of the relay S, which is termed the supervisory relay of the control system, and also to the winding of the relay R, termed the release relay, through normally closed contacts 14 of the relay S. The other terminal of both windings of the relays S and R respectively, connect to the line 2.

The second circuit of the switch S_a between contacts 7 and 10 supplies the winding of the relay A. This ties in with the first circuit between contacts 11 and 12 over the normally open contacts 13 of the relay S.

The contact 11' of the switch S_n connects to the line 1 and contact 12' connects by means of the lead 16 to the contact 12 of the switch S_n . Any number of switches between S_a and S_n serving additional relays in the bank would be similarly connected. In the same way the input side of the second circuit served by the contacts 13 of the relay S connects from the junction point 17 to the contact 18 and utilizing the bus 18 to the contact 10' of the switch S_n , etc.

Referring to the operation of the system, when any one of the switches S_a through S_n is depressed, for example, when S_a is depressed, a current path is established in the first circuit between contacts 11 and 12 energizing the winding of the supervisory relay S. At the same time, a current path is also established to the winding of the relay R through the normally closed contacts 14 of the relay S. While current to the relay R is immediately disconnected upon pickup of the relay S which opens contacts 14, sufficient time elapses for the momentary actuation of the relay R, thus momentarily opening and reclosing the normally closed contacts 4.

When the relay S is actuated, contacts 13 close, completing the second circuit between contacts 7 and 10 of the switch S_a held down by the operator. Current may now flow to the winding of the relay A closing contacts 8 and 9. When the switch S_a is released, the relay S drops out, the current being disconnected between contacts 11 and 12. However, the selected relay A remains closed inasmuch as the holding contacts 8 complete the circuit to the line 1 through the closed contacts 4 of the relay R. The selected relay A, by actuation of the switch S_a , is thus closed and remains closed until another switch is depressed for the selection of another relay.

Assuming that in the next operation it is desired to close relay N, the switch S_n is now depressed and the cycle will be repeated. The contacts 11' and 12' will simultaneously apply current to the relays S and R. The latter receives but a momentary impulse for the interval during which the contacts 14 are closed; however, the resultant momentary opening of the contacts 4 suffices to disconnect the holding current of the relay A which will drop out opening the holding contacts 8 and the utilization circuit contacts 9. While S_n is depressed the winding of the relay N becomes energized through closed contacts 13 of the relay S and closed contacts 7' and 10' of the switch S_n . Since the relay R is now again de-

energized, reclosed contacts 4 complete the circuit for the holding contacts 8' of the relay N. The latter thus remains closed after release of the switch S_n. The utilization circuit connected to the contacts 9' is closed and will remain closed until another of the switches S_a through S_n is actuated.

In practice it has proved that a slight delay in the closing of the relay R is desirable to assure that the contacts 4 remain open a sufficient time to effectuate the dropout of the previously held holding contacts.

For this purpose the relay R may be so chosen as to have operational characteristics which give it a delay in dropout; however, by inserting a capacitance 20 in shunt with the winding of the relay R, the response time of the relay may be extended. A delay time of .0015 sec. is usually sufficient for all practical purposes. It has been found that manual operation of the switches requires more than .0015 sec. for even the most skillful operator.

If it is desired to operate several relays, appropriate switches controlling the selected relays may be simultaneously depressed and such relays will remain closed by their holding contacts. All of these relays will drop out upon later actuation of one or more of the switches.

I claim:

1. In a relay control system for closing any one of a plurality of relays and simultaneously releasing all previously closed relays, a current supply line, a bank of relays, each relay in said bank having holding contacts and contacts for controlling desired circuits, a switch for each relay having contact elements adapted to close, while actuated, simultaneously two distinct circuits supplied from said line, the second of said circuits supplying current to said relays, a supervisory relay having a pair of normally closed contacts and a pair of normally open contacts, said supervisory relay being energized from the first of said distinct circuits upon actuation of any one of said switches, a release relay having normally closed contacts in series between said supply line and all holding contacts of said bank of relays, the winding of said release relay being connected to said first circuit and in series with said normally closed contacts of said supervisory relay, said normally open contacts being in series with said second circuit.

2. In a relay control system for closing any one of a plurality of relays and simultaneously releasing all previously closed relays, a current supply line, a bank of relays, each relay in said bank having holding contacts and contacts for controlling desired circuits, a switch for each relay having contact elements adapted to close, while actuated, simultaneously two distinct circuits supplied from said line, the second of said circuits supplying current to said relays, a supervisory relay having a pair of normally closed contacts and a pair of normally open contacts, said supervisory relay being energized from the first of said distinct circuits upon actuation of any one

of said switches, a release relay having normally closed contacts in series between said supply line and all holding contacts of said bank of relays, the winding of said release relay being connected to said first circuit and in series with said normally closed contacts of said supervisory relay, said normally open contacts of said supervisory relay being in series with said second distinct circuit.

3. In a relay control system for closing any one of a plurality of relays and simultaneously releasing all previously closed relays, a current supply line, a bank of relays, each relay in said bank having holding contacts and contacts for controlling desired circuits, a switch for each relay having contact elements adapted to close, while actuated, simultaneously two distinct circuits supplied from said line, the second of said circuits supplying current to said relays, a supervisory relay having a pair of normally closed contacts and a pair of normally open contacts, said supervisory relay being energized from the first of said distinct circuits upon actuation of any one of said switches, a release relay having normally closed contacts in series between said supply line and all holding contacts of said bank of relays, the winding of said release relay being connected to said first circuit and in series with said normally closed contacts of said supervisory relay, said normally open contacts of said supervisory relay being in series with said second distinct circuit, said release relay having operational characteristics effecting a predetermined delay in dropout time.

4. In a relay control system for closing any one of a plurality of relays and simultaneously releasing all previously closed relays, a current supply line, a bank of relays, each relay in said bank having holding contacts and contacts for controlling desired circuits, a switch for each relay having contact elements adapted to close, while actuated, simultaneously two distinct circuits supplied from said line, the second of said circuits supplying current to said relays, a supervisory relay having a pair of normally closed contacts and a pair of normally open contacts, said supervisory relay being energized from the first of said distinct circuits upon actuation of any one of said switches, a release relay having normally closed contacts in series between said supply line and all holding contacts of said bank of relays, the winding of said release relay being connected to said first circuit and in series with said normally closed contacts of said supervisory relay, said normally open contacts of said supervisory relay being in series with said second distinct circuit, and a capacitor in shunt with the winding of said supervisory relay for extending the dropout time thereof.
